Inventor:

Hanns Klemm.

UNITED STATES PATENT OFFICE.

HANNS KLEMM, OF SINDELFINGEN, GERMANY, ASSIGNOR TO DAIMLER-MOTOREN-GESELLSCHAFT, OF UNTERTURKHEIM, GERMANY, A CORPORATION OF GERMANY.

AXLE FOR FLYING MACHINES.

Application filed June 10, 1924. Serial No. 719,064.

To all whom it may concern:

Be it known that I, HANNS KLEMM, a citizen of the State of Wurttemberg, Germany, residing at Sindelfingen, Bahnhofstrasse 38, Wurttemberg, Germany, have invented certain new and useful Improvements in an Axle for Flying Machines, of which the following is a specification.

It is, as is known, customary with motor-cars, as well as with flying-machines, to arrange springs between the underframe or carriage and the body or hull in order to dampen the shocks arising when the machine starts and when it lands, and to prevent them from being transmitted to the body or hull.

The means employed hitherto for these purposes, i. e. rubber-buffers, spiral-springs, flat springs, and the like, require special members for their connection with the hull, such as struts, axles, staying or stiffening members, and the like, and these additional members frequently cause trouble on account of breaking or becoming disconnected. Furthermore the desired simplification of the carriage must be kept within restricted limits, for the reason that said special members must themselves be provided with other special or additional means in order to obtain an aerodynamically favorable outline.

The object of the invention is to obviate the above-mentioned drawbacks, and I attain that object by so devising the axles of the carriage of the flying-machine that they form springs having a stream-line cross-section and being shaped similarly to supporting planes. I am aware of the fact that these features are singly known but my invention consists in a new combination thereof and one of the effects of this combination is an essential simplification of the carriage. Owing to the stream-line-shaped cross-section of the springs the otherwise required lining-pieces or the like can be dispensed with, and the connection between the carriage and the hull is far simpler. Besides, the total area of the supporting planes is increased by the supporting plane formed by the spring owing to this special shape and arrangement, as is all more fully described, hereinafter.

My invention is illustrated diagrammatically and by way of example in the accompanying drawing in which Figure 1 is a

front view of a carriage (of a flying machine) constructed according to this invention, the hull being merely indicated by a few lines; Figure 2 is a plan of the lefthand part of Fig. 1, and Figs. 3, 4 and 5 are sections through a set of springs in the planes ⁵⁵ *a—a, b—b*, and *c—c* respectively of Fig. 1.

The axle *a* of the carriage of the flying machine is composed of a plurality of superposed flat springs, the shape of which appears from Fig. 2. The running-wheels *b* ⁶⁰ are, in the example shown, attached to the lowermost, i. e. longest and broadest, of said springs. The hull *c* is connected with the axle *a*, that is with the superposed springs, in any known manner. ⁷⁰

The springs are so shaped as to form a kind of supporting plane, and are, therefore, able to increase the buoyancy of the flying machine. The cross-section illustrated in Figs. 3, 4 and 5 show that the combined ⁷⁵ section of the superposed springs form stream-lines. It is also obvious that the carriage of the flying machine is greatly simplified by the composition of the axle of the running-wheel of superposed flat springs having, in their entirety, a section corresponding to the shape of a stream-line. Such an axle offers but slight resistance to its passage through the air and can be used as a means to increase the buoyancy. ⁸⁵

The axle *a*, or the set of springs respectively, may consist of any appropriate kind of wood, such as, ash-tree wood, and the wheel-base may be increased without an increase of the weight, the supporting-base being then correspondingly larger and the elasticity greater. ⁹⁰

I claim:

1. In a flying-machine, in combination: a hull and a carriage comprising wheels and superposed springs, the combined sections of which parallel to the longitudinal axis of the hull form an additional supporting plane and are shaped according to stream-lines, as set forth. ⁹⁵ ¹⁰⁰

2. In a flying machine, an axle composed of laminated springs, the combined cross sections of said springs being shaped according to stream lines. ¹⁰⁵

3. In a flying machine, an axle composed of laminated springs, the width of said springs diminishing toward the top thereof, and the lowermost of said springs being of

a sufficient width to form an additional supporting plane.

4. In a flying machine, an axle composed of laminated springs made of an appropriate kind of wood, the combined cross sections of said springs being shaped according to stream lines.

In testimony whereof I affix my signature in presence of two witnesses.

HANNS KLEMM.
